US00D935813S

(12) **United States Design Patent** (10) Patent No.: **US D935,813 S**
(45) Date of Patent: **** Nov. 16, 2021**

(54) **RETAIL FIXTURE**

- (71) Applicant: **Apple Inc.**, Cupertino, CA (US)
- (72) Inventors: **Allison Inouye**, San Francisco, CA (US); **Jean-Marc Gady**, Los Altos, CA (US); **Ismael Flores Trujano**, San Jose, CA (US); **Gregory Guillaume LeSpinard**, San Jose, CA (US); **Mi Zou**, San Francisco, CA (US); **Po Huang**, San Jose, CA (US); **Wesley Bryan Hamm**, San Francisco, CA (US); **Russell John Kaaihue Heirakuji**, Cupertino, CA (US); **Joshua Robert Edwards**, Santa Cruz, CA (US); **Nicholas E. Corti**, San Francisco, CA (US); **Manuel DeJesus**, San Francisco, CA (US); **Alice Marlin Brugger**, San Francisco, CA (US)
- (73) Assignee: **Apple Inc.**, Cupertino, CA (US)
- (**) Term: **15 Years**
- (21) Appl. No.: **29/765,541**
- (22) Filed: **Jan. 8, 2021**

Related U.S. Application Data

- (63) Continuation of application No. 29/713,506, filed on Nov. 15, 2019, now Pat. No. Des. 907,412.
- (51) **LOC (13) Cl.** **06-06**

(57) **CLAIM**

The ornamental design for a retail fixture, as shown and described.

DESCRIPTION

FIG. 1 is a top front perspective view of a retail fixture showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the retail fixture that form no part of the claimed design.

1 Claim, 4 Drawing Sheets
